UNITED STATES PATENT OFFICE.

FRANK P. HARMON, OF LISBON, TEXAS, ASSIGNOR OF ONE-FOURTH TO THOMAS S. PITCOCK, OF DALLAS, TEXAS.

CENTRIFUGAL PUMP.

Application filed January 6, 1922. Serial No. 527,434.

To all whom it may concern:

Be it known that I, FRANK P. HARMON, a citizen of the United States, residing at Lisbon, in the county of Dallas and State 5 of Texas, have invented certain new and useful Improvements in Centrifugal Pumps, of which the following is a specification.

This invention relates to new and useful improvements in centrifugal pumps.

10 The invention has to do with that class of pumps in which liquid is elevated and discharged by centrifugal action and radial displacement of the liquid when the pump is operated. A particular object of the invention is to provide a pump head and chamber of such a nature that the pump is at all times ready for operation and does not require priming. Another object of 15 the invention is to provide means for retaining a portion of the fluid in the radial passages of the head so that when said head is rotated the liquid will be displaced outwardly and start the pumping operation.

Among other novel features, are a stuffing box connection between the pump shaft and the pipe thru which the liquid is elevated; the provision of a novel form of bearing box and lubricating structure for the pinion which rotates the shaft; a simple 20 and practical head structure, which includes a novel form of liquid retaining means at the outer ends of the ports and a compact and simple form of pump chamber construction, together with a substantial frame 25 and support for the various parts.

A construction designed to carry out the invention will be hereinafter described together with other features of the invention.

The invention will be more readily understood from a reading of the following specification and by reference to the accompanying drawings, in which an example of the invention is shown and wherein:

Fig. 1 is a vertical sectional view of a 45 pump apparatus constructed in accordance with my invention,

Fig. 2 is an elevation of the same on a reduced scale,

Fig. 3 is an enlarged cross section on the 50 line 3—3 of Fig. 2,

Fig. 4 is a plan view of the head, a portion being illustrated in section,

Fig. 5 is a detail of the head, partially 55 in elevation and partially in cross section,

Fig. 6 is a detail of one of the retaining plug structures,

Fig. 7 is a detail of one of the keepers,

Fig. 8 is a detail of the lower end of the pump pipe showing the foot valve, and

Fig. 9 is a detail of a modified form of 60 head structure, being illustrated partially in elevation and partially in cross section.

In the drawings the numeral 10 designates a suitable base on which suitable upright corner posts 11, are mounted. These 65 posts are preferably formed of angle iron, but may be otherwise shaped. The post may be secured to the base by angular brackets 12. A transverse plate 13 is mounted on the upper ends of the corner posts 70 and is preferably circular. A metallic band 14 surrounds the corner posts immediately under said plate, there being four posts the band is square in plan. The plate 75 13 is suitably held in position.

A circular housing 15 is provided at its lower edge with an outwardly directed annular flange 16, which rests upon the plate 13 and is secured thereto by bolts 17. Suitable provision is made for establishing a water-tight joint between the flange and the plate. Within the housing a pump chamber is formed. In one side of the top of the housing is a priming plug 18 which may be removed to introduce a liquid when desired. In the other side of the top of the housing an outlet pipe 19 is connected. At the center of the top of the housing is a dome 20 in which a bushing 21 is disposed. The bushing receives a reduced trunnion 22 90 of a circular head 23.

A hollow shaft 24 passes thru the plate 13 and is screwed into a boss 25 projecting from the center of the lower side of the head, as is best shown in Fig. 5. The boss rests upon the plate 13 and on the underside of said plate a stuffing box 26 of a suitable nature is provided so that the liquid cannot escape from the pump chamber. The hollow or tubular shaft 24 extends downwardly and passes thru a stuffing box 27 which is suspended in a cross plate 28. The stuffing box is provided with ball bearings 29 to receive an annular collar 24' which is immediately below the hub of a pinion 30 mounted on the shaft. A packing gland 31 is arranged in the lower end of the stuffing box and a closure ring 32 is provided

100

95

105

around the hub of said pinion. The closure ring may be raised and oil introduced into the box so that the ball bearings will be immersed in the same and this oil will be retained by the packing gland.

A second cross plate 33 is arranged below the first cross plate and supports a stuffing box casting 34 which has a screw threaded boss 35 depending thru said cross plate. The pipe 36 in which the liquid is elevated is screwed in the said boss. A packing gland 37 is provided at the upper end of the casting and surrounds the lower end of the shaft 24 which terminates immediately above the pipe 36. By this arrangement the pipe 36 is held stationary, while the shaft 24 is permitted to rotate. For fastening the cross plate in position I provide bands 38 which surrounds the support formed by the posts 11. The cross plates rest upon these bands and are fastened by bolts 39, which engage keepers 40 contacting with the under edges of the bands on each side of diagonal corner posts as is best shown in Figs. 1 and 3.

For revolving the shaft 24, I mount a counter shaft 41 in brackets 42 supported on the plate 28. A pulley 43 is mounted on the shaft between the brackets and is suitably driven. A beveled gear 44 is fastened on the end of the shaft 41 and meshes with the pinion 30, whereby the latter is driven. It is to be understood that motion could be applied to the shaft 24 in any suitable manner.

One of the particular features of the invention is the construction of the head 23. At the center of the head a chamber 45 is formed and from this chamber ports or passages 46 radiate and extend laterally to the periphery of said head. In order that all of the liquid may not be displaced from said passages when the head ceases to rotate, plugs 47 are driven into the ends of the passages so as to be flush with the periphery of the head. Each plug is eccentrically counter bored at its upper side so as to provide a port 48 smaller in diameter, than the diameter of the passage. From this it will be seen that the level of the liquid in the passage, when the head is stopped, will be substantially aligned with the bottom of the ports 48, and thus when rotation is again imparted to the head, the liquid remaining in the passages will be displaced outwardly and the pumping action started, thereby making it unnecessary to again prime the pump.

It is pointed out that by revolving the head in a comparatively high rate of speed a large quantity of liquid will be displaced thru the passages 46, thus causing a considerable volume to be elevated thru the pipe 36 and the shaft 24. At the bottom of the pipe 36 I mount a cap 49 in which an in-

wardly opening flap valve 50 is mounted. This valve will open upwardly and admit liquid but prevent the downward passage of liquid from said pipe. So long as the head 23 is rotated the valve will be elevated, but when rotation of the head is ceased, the valve will close and thus retain the liquid which has been elevated. It is obvious that a pump of this character may be operated in various positions and the invention is not to be limited to a horizontally disposed head.

It is also possible to build the head 23 in stages as is shown at 23' in Fig. 9. In this modification the head is provided with the radial passages 46' like those of the head 23, and above these passages is arranged a second set of passages 46^a which may be in staggered relation to the passages 46'. It is obvious that several stages of passages may be employed and the capacity of the pump greatly increased. It is also pointed out that the device will operate in an easy manner and may be adjusted so that the load is carried by the bearings 29, which owing to the short length of the shaft 24 and the rapid rotation of the head, will be reduced to a minimum.

The invention is presented as including all such modifications as come within the scope of the appended claims and various changes and alterations may be made without departing from the spirit of the invention.

What I claim is:

1. In a centrifugal pump, the combination of an upright supporting frame, a plate mounted on the upper end of the frame, a stuffing box carried by the plate, a pump housing mounted on the plate having an outlet, a tubular shaft passing through the stuffing box into the housing, a circular head mounted on the shaft within the housing and having a plurality of radial passages connecting with the tubular shaft, plugs in the outer ends of said passages having elevated discharge openings, whereby a level of fluid is maintained in said passages for priming said head, a transverse support in the frame, means connected with said tubular shaft and mounted on said support for rotating said tubular shaft, and a stationary tubular shaft coupled to the lower end of the rotatable shaft.

2. In a centrifugal pump, the combination of an upright supporting frame, a plate mounted on the upper end of the frame, a stuffing box carried by the plate, a pump housing mounted on the plate having an outlet, a tubular shaft passing through the stuffing box into the housing, a circular head mounted on the shaft within the housing and having a plurality of radial passages connecting with the tubular shaft, plugs in the outer ends of said passages having ele-

vated discharge openings, whereby a level of fluid is maintained in said passages for priming said head, a transverse support in the frame, and a gear mounted fast upon the tubular shaft, a lubricating bearing member carried by said support and supporting said gear, a driving gear engaging the first named gear, a second transverse sup-

port, a second stuffing box mounted on the last named support and receiving the lower 10 end of the tubular rotary shaft, and a stationary tubular shaft connected with the last named stuffing box.

In testimony whereof I affix my signature.

FRANK P. HARMON.
